PULP EJECTOR

Rupert Octavius Stokes, London, England

Application October 2, 1945, Serial No. 619,833
In Great Britain October 4, 1944

8 Claims. (Cl. 302—14)

1

The invention relates to pulp ejectors, that is mechanism by which settled solids can be drawn from the bottom of an under water pulp storage tank. The problem arises most frequently in the case of sand but it is met with whenever a finely divided solid in substantial quantity is suspended for storage or handling in a liquid and is liable to settle. The term "sand" used hereinafter must be considered as including any such solid, "pulp" being a suspension of sand so defined in water.

According to the invention the pulp ejector comprises three tubular members one within another and each with an open end of which the outer and middle ones project downwards into the sand vessel and terminate therein and the inner one is adapted to receive the pulp and pass it to the discharge, while provision is made for a supply of water to the space between the outer and middle tubular members to keep the sand in a teetering state and for a pressure difference to make the pulp so produced flow away through the inner member.

The tubular members are not necessarily of circular cross section. If they are of rectangular cross section, the pulp is discharged in the form of a ribbon, which is advantageous in such cases as delivery of the pulp to a filter drum.

Preferably the middle tubular member is adjustable in an up and down direction to vary its distance from the vessel bottom and so to modify the thickness of pulp discharged.

Where the pulp is discharged in an upward direction all three tubular members have their ends opening downwards. The middle member is conveniently in the form of a sleeve, which permits some of the water to enter between it and the inner member. If the outlet is well below the water level in the vessel, the pressure difference is provided by the hydrostatic head due to the water in the vessel, and no additional pumping means will be required.

For discharge in a downward direction the inner member will be a pipe end projecting upwards through the bottom of the vessel, and the middle member may take the form of a cap surrounding the inner member. In this case the full hydrostatic head of the water in the vessel down to the final discharge provides the required pressure difference, but discharge can be stopped by cutting off the water supply, since the sand will then pack around the ejector.

The invention is illustrated by two forms of construction shown in the accompanying drawings, in which

Figure 1 is a sectional elevation of a pulp stor-

2

age tank or hopper with ancillary apparatus including an ejector according to the invention.

Figures 2 and 3 are enlarged views of the ejector shown in Figure 1 to explain its operation.

Figure 4 is a sectional elevation of another form of ejector, and

Figure 5 is a similar view of the upper part of the storage tank to which the ejector of Figure 4 is fitted.

10 Referring first to Figure 1, a hopper 1 for storing sand or pulp has a bottom generally in the shape of an inverted cone, near the apex of which the ejector is fitted, as will be described later. The sand is fed by a launder 2 into a feed box 3 with open bottom. The wall of the hopper 1 terminates below the normal level of the water in the hopper and is surrounded by an outer wall 4 to form an annular clear water trough 5. Excess water is discharged by an overflow 6.

15 20 For discharging the pulp a curved pipe 7 terminates at one end near the apex of the cone, and at its other end, outside the hopper 1, a valve 8 is fitted, which can be opened and closed by lever gear 9. The valve 8 discharges into a launder 10.

25 To regulate the discharge of pulp through the pipe 7, and indeed to make such a discharge possible, an ejector is fitted, of which the lower end of the pipe 7 forms a part. A tube 11 suspended 30 from a platform 12 above the hopper 1 carries at its lower end a cylindrical casing 13 open at its lower end but otherwise closed. The casing 13 serves to support the lower end of the pipe 7, which passes through the side thereof by a water tight joint.

35 A rod 14 is movable inside the tube 11 through a range of heights by means of lever gear 15 and carries at its lower end a sleeve 16 with its lower edge projecting a little below that of the casing 13. The sleeve 16 is between the casing 13 and the lower end of the pipe 7, having a clearance hole by which the bent part of the pipe 7 passes out. This construction is seen more clearly in Figures 2 and 3 which will be referred to later.

40 45 For normal operation a horizontal pipe 17 connects the trough 5 to the pipe 11, and a valve 18 in the pipe 7 with hand wheel 19 accessible from the platform 12 serves to control the water flow in the pipe 17. A second water supply for starting and for emergencies comes through a pipe 20 to the tube 11 and is controlled by a valve 21, which also has its hand wheel 22 accessible from the platform 12.

50 In normal use the hopper 1 will contain a thick mass of settled sand with more or less clear water

above it. When it is desired to discharge sand from the hopper, the sleeve 16 is raised to the required extent above the bottom flat of the hopper 1 and the clear water valve 18 and the discharge valve 8 are opened. Little water can percolate through the bed of sand to the outlet bend 7, since it would suffer a considerable loss of head due to friction.

On the other hand water enters the valve 18 and passes down the central vertical tube 11 and cylindrical casing 13 with little loss of head. Some of this water passes between the casing 13 and the sleeve 16, causing the sand at the bottom to teeter and thus considerably reduce its friction. Other water flows down between the sleeve 16 and the outlet bend 7 and carries away the teetering sand to the discharge valve 8.

The position of the sleeve 16 governs the thickness of the pulp discharged. If the sleeve is nearly down on the flat, a thin pulp is discharged as indicated by the narrow column of dots 23 in Figure 3, and, when it is in its highest position as shown in Figure 2 the thickest pulp consistent with the valve setting is discharged. The thicker pulp is indicated by the wider column of dots 24. In both figures the arrows denote the flow. The water supply valve 21 is provided for emergencies only, for instance when there is a chokage due to the apparatus having been shut down for a considerable time.

It is not always necessary for water to flow down between the outlet bend and the sleeve. In the downward discharge form of construction shown in Figures 4 and 5 there is no corresponding flow of water, all the water carrying the ejected pulp taking part in producing the teeter.

In this form of construction the hopper 25 is cylindrical at its upper part and has an open top surrounded by a launder 26 with a short overflow pipe 27. At the centre of the hopper and level with the top is a feed well 28. A water pipe 29 extends vertically through the centre of the feed well 28 nearly to the bottom of the hopper and has a T joint 30 in the feed well 28 to receive a horizontal pipe 31 from the launder 26. The horizontal pipe 31 is for carrying clear water overflowing from the hopper 25 into the launder for the purpose of discharging the hopper from the bottom, and the upper part of the vertical pipe 29 is for an additional feed of fresh water for the same purpose when starting after a long shut down. Both branches have regulating valves 32 and 33.

The vertical pipe terminates at the lower end in a cylindro-conical hood or casing 34 which may if desired be supported from the bottom of the hopper by vertical legs or pins so as to leave a practically uninterrupted cylindrical sand inlet aperture below the open end of the casing. The top of the casing is closed except for the inlet by which the vertical pipe 29 enters.

A discharge bend 35 projects upwards through the bottom of the hopper 25 coaxially with the casing 34. The top edge of the bend 35 is about level with the bottom edge of the casing 34. A rod 36 coaxial with the casing 34 and the top end of the bend 35 passes through the side of the bend by a gland 37. A cylindrical cap 38 closed at the top is fixed to the top of the rod 36 and is clear of both the casing 34 and the discharge bend 35. The lower end of the rod 36 is provided with a hand wheel and screw device 39 by means of which the cap 38 can be raised or lowered in relation to the cylindrical casing 34 and discharge bend 35 to stop or adjust the flow of pulp.

When it is desired to extract sand from the hopper 25, the valve 33 is opened and, if necessary, also the valve 32. The water flowing down between the casing 34 and the cap 38 sets the sand at this place into a condition of teeter and flows away under the cap 38 and down the bend 35 carrying with it the sand as a pulp of thickness dependent as before on the vertical position of the cap 38.

10 It will be seen that by means of the invention pulp can be discharged from a hopper by gravity only, the hydrostatic head being sufficient to ensure an adequate flow, whereas in known constructions having only two tubular members it is necessary to supply pressure water to keep the pulp in teeter and a suction pump to lift the pulp from the bottom of the hopper. In the case of the invention a pressure water supply is only provided, as explained above, to overcome a chokage on starting after a long period of rest with a considerable quantity of sand in the hopper. After getting the flow started the water supply may be cut off, the sand being carried to discharge by means of the water supplied with the feed.

25 What I claim is:

1. A pulp ejector in a vessel from which pulp is to be discharged comprising a first tubular member projecting downwards into the vessel and terminating there with an open end, a second tubular member projecting downwards within and spaced from the first and likewise terminating there with an open end, a third tubular member having an open end within and spaced from the second tubular member and having its other end arranged for the discharge of pulp outside the vessel, means for supplying water to the space between the first and second tubular members, and means for providing a pressure difference to discharge through the third tubular member the pulp teetering due to the water supplied to the space between the first and second tubular members.

2. A pulp ejector in a vessel from which pulp is to be discharged comprising a first tubular member projecting downwards into the vessel and terminating there with an open end, a second tubular member projecting downwards within and spaced from the first and likewise terminating there with an open end, a third tubular member having an open end within and spaced from the second tubular member and having its other end arranged for the discharge of pulp outside the vessel, a connection by which the supernatant water in the vessel can flow into the space between the first and second tubular members, and means for providing a pressure difference to discharge through the third tubular member the pulp teetering due to the water supplied to the space between the first and second tubular members.

3. A pulp ejector in a vessel from which pulp is to be discharged comprising a first tubular member projecting downwards into the vessel and terminating there with an open end, a second tubular member projecting downwards within and spaced from the first and likewise terminating there with an open end, a third tubular member having an open end within and spaced from the second tubular member and having its other end outside the vessel at a lower level than the normal liquid level within the vessel, and a connection by which the supernatant water in the vessel can flow into the space between the first and second tubular members.

75 4. A pulp ejector in a vessel from which pulp is

to be discharged comprising a first tubular member projecting downwards into the vessel and terminating there with an open end, a second tubular member projecting downwards within and spaced from the first and likewise terminating there with an open end, a third tubular member having an open end also projecting downwards within and spaced from the second tubular member, the said third tubular member passing through the lateral wall of the vessel and having its other end terminating outside the vessel at a lower level than the normal liquid level within the vessel and a connection by which the supernatant water in the vessel can flow into the space between the first and second tubular members.

5. A pulp ejector in a vessel from which pulp is to be discharged comprising a first tubular member projecting downwards into the vessel and terminating there with an open end, a second tubular member projecting downwards within and spaced from the first and likewise terminating there with an open end, a third tubular member having an open end projecting upwards within and spaced from the second tubular member, the said third tubular member passing through the bottom of the vessel to a discharge point therebelow and a connection by which the supernatant water in the vessel can flow into the space between the first and second tubular members.

6. A pulp ejector in a vessel from which pulp is to be discharged comprising a first tubular member projecting downwards into the vessel and terminating there with an open end, a second tubular member in the form of a cap closed at the top and open at the bottom and located partly within and spaced from the first tubular member, a third tubular member having an open end projecting upwards within and spaced from the cap and having its other end below the vessel, and a connection by which the supernatant water in

the vessel can flow into the first tubular member at the top thereof.

7. A pulp ejector in a vessel from which pulp is to be discharged comprising a first tubular member projecting downwards into the vessel and terminating there with an open end, a second tubular member projecting downwards within and spaced from the first and likewise terminating there with an open end, a third tubular member having an open end within and spaced from the second tubular member and having its other end arranged for the discharge of pulp outside the vessel, means for supplying water to the space between the first and second tubular members, means for providing a pressure difference to discharge through the third tubular member the pulp teetering due to the water supplied to the space between the first and second tubular members and means for adjusting the position of the second tubular member in an up and down direction.

8. A pulp ejector in a vessel from which pulp is to be discharged comprising a first tubular member of circular section projecting downwards into the vessel and terminating there with an open end, a second tubular member of circular section concentric with the first projecting downwards within and spaced from the first and likewise terminating there with an open end, a third tubular member having an open end of circular section located concentrically within and spaced from the second tubular member and having its other end arranged for the discharge of pulp outside the vessel, means for supplying water to the space between the first and second tubular members, and means for providing a pressure difference to discharge through the third tubular member the pulp teetering due to the water supplied to the space between the first and second tubular members.

40 RUPERT OCTAVIUS STOKES.
